UNITED STATES PATENT OFFICE

ROMUALDO SPANO, OF UTICA, NEW YORK

CURTAIN DRYING FRAME

Application filed July 16, 1932. Serial No. 622,965.

This invention relates to certain new and useful improvements in curtain drying frame.

The primary object of the invention is to provide an extensible curtain drying frame 5 with a novel form of curtain clamp carried by the bars of the frame for securely retaining a curtain in stretched condition on the frame.

A further object of the invention is to provide a curtain drying frame comprising a series of hinged clamp members having screw carried clamp arms engageable therewith for retaining the clamp members in engaged relation with the curtain being stretched.

A still further object of the invention is to provide a curtain stretcher of the foregoing character wherein the clamp members may be shifted longitudinally of a carrying bar to permit equidistant positioning of the clamp member when the bars are adjusted to support curtains of different sizes.

With the above and other objects in view that will become apparent as the nature of the invention is better understood, the same 25 consists in the novel form, combination and arrangement of parts hereinafter more fully described, shown in the accompanying drawing and claimed.

In the drawing:

Figure 1 is a plan view of a curtain stretching frame carrying curtain clamping members constructed in accordance with the present invention;

Figure 2 is a top plan view of one of the clamp members in closed position;

Figure 3 is a top plan view of one of the clamp members in open position;

Figure 4 is a detail sectional view taken on line 4-4 of Figure 1, showing the adjustable mounting of a clamp member; and

Figure 5 is an edge elevational view of a modified form of one of the fixed clamping members.

Referring more in detail to the accompanying drawing and particularly to Figure 1, there is illustrated a curtain drying frame comprising longitudinally extending bars 10 and cross bars 11 relatively adjustable to accommodate the mounting of curtains of different sizes.

A series of adjustably mounted curtain engaging clamp members 12 is carried by each cross bar 11 of the drying frame while curtain engaging clamp members 13 are carried by the longitudinally extending frame bars 55 10. Each of the curtain engaging clamping members 12 as shown in Figures 2 to 5 include a rectangular block 14 having a clamping strip 15 hinged to one side face thereof as at 16 with the free edge of the clamping strip 15 when in clamping position being in the plane of the adjacent edge of the block 14. A series of curtain engaging pins 17 carried by a plate 18 anchored to the inner face of the clamping strip 15 are disposed 60 adjacent the free edge of the clamping strip and are adapted to be received in openings or depressions on the outer face adjacent the edge of the block 14 as shown in Figure 3 and designated by the reference character 19. 70

Each block 14 carries a transversely extending threaded bearing 20 including a screw rod 21 upon the outer end of which and overlying the outer face of the clamping block 14 is mounted a clamping arm 22 carrying a hand grip 23 to facilitate manipulation thereof. The outer face of the clamping strip 15 carries an arcuate wear plate 24 secured in position thereon by angularly bending the ends thereof as at 25 and securing the angularly bent ends as at 26 to the hinged side edge of the clamping strip 15, an angle lug projection 27 intermediate the ends of the arcuate wear plate 24 being engaged with the outer edge of the clamping strip and secured thereto as at 28. The outer end of the clamping arm 22 is movable over the wear plate 25 as shown in Figures 1 and 2 for retaining the clamping strip 15 in clamping engagement with an edge of a curtain or the like. 80 85 90

The clamping members 12 are illustrated as being adjustably mounted upon cross bars 11 of the drying frame and to accomplish this adjustment, the rear face of each block 14 carries a rib 29 slidable in a groove 30 in the bar 11 and said bar is also provided with a longitudinal slot 31 through which the screw rod 21 projects to receive on the projecting end thereof a washer 32 engageable with the adjacent face of the frame bar 11 at 95 100

opposite sides of the slot 31 and also a clamping wing nut 33. Upon loosening the wing nut 33, the block 14 carrying the clamping strip 15 together with the screw rod 21 may 5 be shifted longitudinally of the frame bar 11 for the positioning of the clamping member at any point desired.

The clamping members 13 carried by the longitudinally extending frame bars 10 may 10 also be adjustably mounted as the clamping members 12, but the members 13 are illustrated as having the screw rod threaded through the frame bar 10 with the clamping strips 15a hinged directly on the frame bar 15 10.

From the above detailed description of the invention, it is believed that the construction and operation thereof will at once be apparent and while there is herein shown and 20 described the preferred embodiment of the invention, it is nevertheless to be understood, that minor changes may be made therein without departing from the spirit and scope of the invention as claimed.

25 I claim:—

1. In a curtain drying frame, crossed frame bars, curtain clamping members carried thereby and each including a hinged clamping strip, a screw rod supported on the frame 30 bar and a clamping arm carried by the screw rod and movable into engagement with the clamping strip for holding the strip in closed clamping position, and an arcuate wear-strip interposed between the clamping strip and 35 clamping arm and having angle ends overlying an edge of the clamping strip and secured thereto and an angle strip intermediate the ends of the wear strip overlying the other edge of the clamping strip and secured 40 thereto.

2. In a curtain drying frame, crossed frame bars, curtain clamping members carried thereby and each including a hinged clamping strip, a screw rod supported on the frame 45 bar and a clamping arm carried by the screw rod and movable into engagement with the clamping strip for holding the strip in closed clamping position, a block carrying the clamping strip and through which the screw 50 rod extends, the frame bar being longitudinally slotted for the passage of the screw rod and a clamping nut on the other end of the screw rod for holding the block anchored to the frame bar.

55 3. In a curtain drying frame, crossed frame bars, curtain clamping members carried thereby and each including a hinged clamping strip, a screw rod supported on the frame 60 bar and a clamping arm carried by the screw rod and movable into engagement with the clamping strip for holding the strip in closed clamping position, an arcuate wear-strip interposed between the clamping strip and 65 clamping arm and having angle ends overlying an edge of the clamping strip and secured

thereto and an angle strip intermediate the ends of the wear strip overlying the other edge of the clamping strip and secured thereto, a block carrying the clamping strip and through which the screw rod extends, the frame bar being longitudinally slotted for the passage of the screw rod and a clamping nut on the other end of the screw rod for holding the block anchored to the frame bar. 70

4. In a curtain drying frame, crossed frame bars, a curtain clamping members carried thereby and each including a hinged clamping strip, a screw rod supported on the frame bar and a clamping arm carried by the screw rod and movable into engagement with the clamping strip for holding the strip in closed clamping position, a block carrying the clamping strip and through which the screw rod extends, the frame bar being longitudinally slotted for the passage of the screw 75 rod and a clamping nut on the other end of the screw rod for holding the block anchored to the frame bar, a guide rib carried by the block and the frame bar being longitudinally grooved for the reception of the guide rib. 80

5. In a curtain drying frame, crossed frame bars, curtain clamping members carried thereby and each including a hinged clamping strip, a screw rod supported on the frame bar and a clamping arm carried by the screw rod and movable into engagement with the clamping strip for holding the strip in closed clamping position, an arcuate wear-strip interposed between the clamping strip and clamping arm and having angle ends overlying an edge of the clamping strip and secured thereto and an angle strip intermediate the ends of the wear strip overlying the other edge of the clamping strip and secured thereto, a block carrying the clamping strip and through which the screw rod extends, the frame bar being longitudinally slotted for the passage of the screw rod and a clamping nut on the other end of the screw rod for holding the block anchored to the frame bar, a guide rib carried by the block and the frame bar being longitudinally grooved for the reception of the guide rib. 95

100 In testimony whereof I affix my signature.
